(57) **CLAIM**

The ornamental design for a watch casing and portion of a strap, as shown and described.

DESCRIPTION

FIG. 1 is a top plan view of a watch casing and portion of a strap showing my new design;

FIG. 2 is a left side elevational view thereof;

FIG. 3 is a right side elevational view thereof;

FIG. 4 is a first end elevational view thereof;

FIG. 5 is a second end elevational view thereof; and,

FIG. 6 is a bottom plan view.

The broken-line showings are environmental only and form no part of the claimed design.

The speckled dots are intended to illustrate a contrast in color and/or material used to construct and illustrate the claimed invention. The fact that the drawings illustrate dots, in and of itself, is not material to the invention.
